UNITED STATES PATENT OFFICE.

MORTEN MORTENSEN, OF HYDE PARK, MASSACHUSETTS, ASSIGNOR TO OLE MARTIN DAHL,
OF ROXBURY, BOSTON, MASSACHUSETTS.

ROTARY PUMP.

No. 919,058.

Specification of Letters Patent.

Patented April 20, 1909.

Application filed December 10, 1907. Serial No. 405,930.

To all whom it may concern:

Be it known that I, MORTEN MORTENSEN, a subject of Norway, residing at Hyde Park, in the county of Norfolk and State of Massachusetts, have invented certain new and useful Improvements in Rotary Pumps, of which the following is a specification, reference being had to the accompanying drawings.

10 My invention relates to improvements in rotary pumps; and an object of my invention is to provide a rotary pump which will be simple in construction, comparatively cheap in manufacture and most efficient in 15 use.

In the drawings illustrating the principle of my invention and the best mode now known to me of applying that principle, Figure 1 is a side elevation of my new pump; 20 Fig. 2 is a central vertical section thereof; Fig. 3 is a view of the interior of the pump, the face-plate being shown removed; Fig. 4 shows the inner face of the face-plate; Fig. 5 is a view looking in the direction of the arrow 25 in Fig. 1; Fig. 6 is a section on the line A—A of Fig. 1; Fig. 7 is a detail in perspective of the drum-carrier; Fig. 8 is a detail showing the slidable abutment; Fig. 9 is a detail showing the rear face of the drum; Fig. 10 is 30 a section on the line B—B of Fig. 3; Fig. 11 is a detail showing the inlet and outlet ports; and Fig. 12 is a detail showing the drum in plan.

The casing *a* is cylindrical in shape and is 35 provided with bracket-lugs *b* by which the casing may be attached to any suitable support. To the casing *a* is fastened by screw-bolts *c* the face-plate *d*. The inner face of the latter is formed with a ring-shaped or 40 cylindrical wall *e* which is concentric with the face-plate and from which extends a radial partition wall *f* formed with a groove *g* in its inner radial edge. The face-plate *d* is further formed with a circular groove *h* in 45 which is placed packing *i* that serves to seal the joint between the face-plate and the casing. In the latter is journaled a shaft *j* upon the outer end of which is mounted a driving wheel *k* and upon the inner end of 50 which is mounted a drum-carrier *m* consisting of a disk *n* from which projects inwardly the stud *o* around which is coiled a spring wire *p* one end of which is held fast in the notch or recess *q* in the edge of the disk and 55 the other end of which presses outwardly the

drum-plate *r* which is pivoted at *s* on the disk *n* and which is formed with a pivot-stud *t*. The drum-plate *r* is further formed with a notch or recess *u* adapted to receive a stop-lug *v* which projects from the disk *n* and 60 limits the inward movement of the drum-plate.

Upon the pivot-stud *t* is mounted the hollow drum *w*, the former passing through a central hole *x* in the latter; and by reference 65 to the drawings, it will be seen that the drum *w* is mounted eccentrically with respect to the shaft *j* which drives it through the drum-carrier *m*. Near its peripheral edge the hollow drum *w* is formed with a recess *y* in the 70 bottom of which is formed a hole *z*. The recess is shaped to receive the head *z* of the slidable abutment *2*, while the hole *z* in its bottom is adapted to receive the stud *4* which projects from the head *z*, whereby the hollow 75 drum *w* is pivotally connected to the inner end of the slidable abutment *2*. The latter works back and forth in a stuffing-box *6*, as the drum *w* moves in the casing; and it is guided by the engagement of its rib *5* in the 80 groove *g* in the radial partition wall *f*. The hollow drum *w* is formed with an opening *7* in its cylindrical wall through which opening passes the radial partition wall *f* just referred to, whereby the opening *7* is divided into an 85 inlet opening *8* and an outlet opening *9*. The casing *a* is formed with an inlet port *10* and an outlet port *11*; and the former communicates with the intake pipe *12*, while the latter communicates with the discharge pipe 90 *13*. The outer end of the radial partition wall extends to and abuts against the part *14* of the casing *a* which separates the ports *10* and *11*.

From the foregoing description and an 95 inspection of the drawings, it will be noted that the hollow drum *w* is held firmly but with a yielding pressure against the inner cylindrical wall of the chamber *15*. Hence, the tendency will be to cause the drum and 100 the wall of the chamber to wear to a true fit, if they are not exactly so at the start; and, further, allowance is made by the yielding nature of the mounting for the passage of any sand or grit which enters between the drum 105 and the opposed wall against which it rubs. As the driving shaft *j* turns, the hollow drum *w* is carried back and forth along the radial partition wall *f* and also around the chamber *15*, rubbing against the wall thereof. Water 110

will be admitted to the chamber 15 between the wall of the latter and the wall of the drum; and water will also be admitted to the inside of the drum *w* in the space between its wall and the wall *f*. As the drum *w* moves around in the chamber 15, it will force the water out through the opening 9, port 11 and discharge pipe 13.

I claim:

- 10 In a rotary pump of the character described, the combination with a casing formed with a recess and with inlet and outlet ports; a driving shaft journaled in said casing; a disk mounted on the inner end of said shaft and in said recess; a spring-pressed drum-plate pivotally mounted on said disk; a hollow cylindrical drum pivotally mounted on said drum-plate and formed with an opening

which communicates with said ports; a slide-able abutment pivotally connected to said drum and formed with a guide-rib; and a face-plate which is fastened to said casing and is formed with an inwardly-extending cylindrical flange and with a partition wall grooved to receive said guide-rib, said flange 25 lying within said hollow drum.

In witness whereof I have hereunto set my hand at Boston, in the county of Suffolk and State of Massachusetts this third day of December, 1907, in the presence of the two 30 undersigned witnesses.

MORTEN MORTENSEN.
